(57) **CLAIM**

The ornamental design for a calibration chamber for prostate mechanical imaging probe, as shown and described.

DESCRIPTION

This invention was made with government support under SBIR grant R44CA082620 awarded by National Cancer Institute, National Institutes of Health. The government has certain rights in the invention.

FIG. 1 is a perspective view of a calibration chamber for prostate mechanical imaging probe;

FIG. 2 is a side view thereof, the opposite side being identical;

FIG. 3 is a top view thereof;

FIG. 4 is a bottom view thereof. Details shown in broken lines form no part of the claimed design;

FIG. 5 is a front view thereof; and,

FIG. 6 is a rear view thereof.

1 Claim, 6 Drawing Sheets
